(57) **CLAIM**

I claim the ornamental design for a curved conical set screw, as shown and described.

DESCRIPTION

FIG. 1 is a top side perspective view of a curved conical set screw;
FIG. 2 is a bottom side perspective view thereof;
FIG. 3 is a first side view thereof;
FIG. 4 is a second side view thereof;
FIG. 5 is a cross-sectional view thereof; and,
FIG. 6 is a top view thereof.
